X-RAY TRANSFORMER CONTROL

Edwin Russell Goldfield, University Heights, Ohio,
assignor to Picker X-Ray Corporation, Waite
Manufacturing Division, Inc., Cleveland, Ohio,
a corporation of Ohio

Application December 23, 1946, Serial No. 717,890

8 Claims. (Cl. 250—95)

1

This invention relates to improvements in X-ray transformer controls and more particularly to a means for securing optimum transformer conditions for two separate X-ray tubes having different kilovoltage ratings.

The need for my invention is apparent in X-ray tube systems utilizing one tube for superficial therapy at 140 kv., and another tube for radiography at ratings running up to 110 kv. It is a recognized fact that the transformer performance is very largely governed by the reactance of the winding more than anything else. This reactance might be expressed as a function of the coupling of the copper to the iron circuit and also as a function of the square of the number of turns. Obviously then, the best way to secure good performance is to reduce the turns and crowd the iron as tightly as possible against the copper. Since the proximity of the copper to the iron is dependent on the top voltage in the secondary of the transformer, one can get better coupling of copper to iron at 110 kv. than one can at 140 kv. Likewise, the secondary turns may be reduced in direct proportion. Heretofore, in X-ray systems of the type discussed herein, the optimum transformer design for radiographic work has been compromised in order to secure sufficient voltage for superficial therapy. It is an object of the present invention to do away with these conditions so as to provide very advantageous transformer conditions for both radiography and superficial therapy.

Another object of the present invention is to provide a control of the "Monitor" type wherein a single control member operates selectively upon different decks to simultaneously set up predetermined conditions for the X-ray operation to be performed. For instance, at the time that the 110 kv. X-ray tube is selected for radiography, it is customary to select the proper filament current for the X-ray tube, change the valve tube temperature, connect in a suitable timer, and in general, to change all of the factors in the control circuits to those which are suitable for radiography. In the same way, another setting of the "Monitor" control will select other values of the above-mentioned factors suitable for use in connection with superficial therapy use of the 140 kv. X-ray tube. The present invention comprises means operated automatically upon the selection of suitable control circuits for radiography or for therapy, to select at the same time proper transformer conditions whereby optimum results will be secured whatever the voltage used.

2

Other objects of the invention include novel means arranged to carry out the above described purposes which will be clearly understood from the accompanying drawing and specification and the essential features of which will be set forth in the appended claims.

The drawing shows a diagrammatic view of electrical circuits and associated apparatus showing one embodiment of my invention.

10 In the drawing, I have shown an X-ray tube 10 for use under radiographic conditions up to 110 kv. A second X-ray tube 11 is suitable for superficial therapy at 140 kv. Suitable means is provided for energizing these tubes including a high tension transformer means 12 and a four-valve rectifier circuit 13 shown diagrammatically for simplicity. The high tension alternating current is fed to the rectifier circuit through lines 16 and 17. The rectified current is fed to the X-ray tube anode through line 18 and switch 46, and to the tube filament through lines 19 and 80 and switch 48.

Filament current for the X-ray tubes is supplied through filament transformer 14 which is 25 a two-part transformer having one part 14a for providing a smaller focal spot in connection with therapy, and a second portion 14b for operating a larger focal spot in connection with radiography. The secondary 14a is connected to the tube filament by line 81 and switch 47, and by lines 82 and 80 and switch 48. The secondary 14b is connected to the tube filament by line 83 and switch 49, and by lines 82 and 80 and switch 48. The primary current for the filament transformer is supplied from L1, L2, through a milliammeter limiting resistance 15 located on one 30 deck of the "Monitor" control system and through a focal spot selective switch 16 located on another deck of the "Monitor" system. For simplicity, I have shown a control knob 17 for manipulating a shaft 18 which extends to various decks of the "Monitor" system, only four of which are shown, but the use of which is familiar to those skilled in this art. In the position shown in the drawing, the switch arm 15a on one deck is in a position corresponding to the position of switch arm 16 on the other deck. In the position shown in full lines, the "Monitor" 35 is set for radiography. The switch 16 is set to energize the portion 14b of the filament transformer so as to supply the large focal spot of the X-ray tube. The switch 15a at the same time selects the proper milliammeter limiting resistance for this operation.

55 At the same time, the arm 19 on another deck

of the "Monitor" control is in contact with one of the control buttons 20 for selecting a suitable timer for radiography. As shown in the lower portion of the diagram, this timer circuit receives its power from a low voltage source L3, L4, through line 21, arm 19, buttons 20 and line 22, through lines 23 and 24 to energize the timer motor 25, and then through lines 26, 27, and 28, back to L4. At the same time, another circuit leads from line 23 through line 29, radiography push button 30, line 31, the winding of solenoid 32, relay 33 and line 34, back to lines 27 and 28 to complete the circuit. Another circuit from line 22 leads through line 35, normally closed switch 36 to the normally open switch 37 which is controlled by relay 33. When both switches 36 and 37 are closed, a circuit is completed through line 38, relay 39 and line 28, back to the other side of the line. The relay 39 controls switch 40 which closes when the relay 39 is energized to cause an exposure. The switch 40 is in the circuit running from the electrical source L5, L6, through suitable connections later described, for energizing the primary of transformer 12. Returning to the radiographic timer, when motor 25 is running, it drives a portion 41a of a clutch mechanism shown diagrammatically. This clutch mechanism drives a part 41b which in turn carries an arm 42 adapted to open switch 36 when the timer has run a predetermined distance. The position of the clutch is controlled by the armature 32a of the solenoid having the winding 32. The action is such that the clutch is normally released except when the relay winding 32 is energized upon closing of the button 30. This starts the rotation of the part 41b which carries the timing arm 42. At the same time, relay 33 is energized and closes switch 37 so as to start an exposure. When the exposure is completed for the time set, the arm 42 opens switch 36 stopping the exposure.

When the "Monitor" is set in the position shown in the drawing, I have arranged a fourth switch arm 43 for controlling the connection of the various operating circuits to either tube 10 or 11 corresponding to the various control circuits selected by the arms 15a, 16, 19 (and any other controlling arms connected with the "Monitor" system). This switch arm 43 controls the operation of an electrical device such as the motor indicated diagrammatically at 44 which turns a shaft 45 movable with which is a switch 46 for connecting the anode of one or the other of the X-ray tubes, switches 47, 48 and 49 for connecting the cathode of one or the other of the X-ray tubes, switches 50 and 51 for making a certain transformer secondary connection as will later appear, and switch 52 for making a certain transformer primary connection as will later appear. The operating circuit for the switch controlling motor 44 is from the electrical source L3 through line 53, motor 44, line 54, switch 55, which in the full line position completes a circuit through lines 56 and 57 to button 43a which cooperates with switch arm 43 to complete a circuit through line 58 to the source L4. In its dot-dash position, the switch 55 completes a circuit through line 59 to one of the buttons 43b which coacts with switch arm 43 to complete the circuit to the source L4. Movable with shaft 45 is a generally semi-circular cam 60 which in the full line position permits the closure of switch 55 (by means not shown) to the full line position of the drawing. When the motor 44 has rotated shaft 45 through 180

degrees the cam 60 takes the dot-dash position indicated in the drawing, which moves switch 55 from the full line position to the dot-dash position indicated. Another switch 61 provides a connection from line 56 through line 62 to line 59. A cam 63 movable with shaft 45 opens switch 61 upon each revolution of shaft 45 through 180 degrees. Means not shown is provided for normally closing switch 61 when permitted by cam 63. The operation of this portion of the apparatus should now be apparent. When the switch arm 43 is in the full line position shown in the drawing, the switch 55 is also in the full line position, and the motor operating circuit is open in both places, namely, at switch 61 and at line 64. However, when switch arm 43 is moved to the dot-dash position indicated on the drawing, the circuit from motor 44 is completed through lines 57 and 56, switch 55 and line 54. The motor then starts to turn causing cam 60 to move to the dot-dash position indicated, so as to move switch 55 to the dot-dash position shown in the drawing. Switch 61 closes during a portion of a half cycle and opens switch 61 at the proper time to stop the cam 60 in its dot-dash position. Obviously, as long as switch arm 43 remains in its dot-dash position, the motor circuit through lines 57 and 56 is open. Upon the return of switch arm 43 to its full line position, the circuit for motor 44 then becomes closed through lines 59 and 64, switch 55 (in its dot-dash position) and line 54. Thereupon, another half cycle of motor 44 occurs returning the parts to the full line position indicated in the drawing.

I provide a novel high tension transformer to cooperate with the mechanism and circuits, thus far described. The transformer primary 12a is always connected by line 65 with the source L5 and is connected by line 66 with the source L6 whenever the exposure switch 40 is closed. The transformer secondary 12b with its central ground 67 is always utilized whether tube 10 or tube 11 is operated. The transformer primaries 12c and 12e are energized only when tube 11 is operated, as will presently appear, and their corresponding secondaries 12d and 12f, respectively, are in series with the secondary 12b through lines 68 and 69 whenever tube 11 is operated, as will presently appear, whereas, the secondary 12d is shunted through lines 10 and 11 whenever tube 10 is operated and the transformer secondary 12f is shunted through lines 12 and 13 whenever tube 10 is operated. The switches 59 and 61, previously referred to, are in the full line position when tube 10 is operated, at which time, they close the circuits 72, 73 and 70, 71, respectively, to complete the shunts mentioned above. When the switches 50 and 51 are in the dot-dash position corresponding to the operation of tube 11, the shunts are open and the secondaries 12d and 12f are in series with the secondaries 12b for the higher voltage operation. The primaries 12c and 12e are energized from the source L5 through line 74, switch 52 in its dot-dash position and line 75, both circuits being completed through line 66 to the source L6.

When the "Monitor" knob 17 is turned to place the switch arms on the various decks in the dot-dash position in the drawing, the device is set for therapy using the X-ray tube 11. At this time the switch arm 46 is set to energize the primary of the filament transformer portion 14a which corresponds to the smaller focal spot. At the same time, more of the resistance 15 is cut into

the circuit by the switch arm 15a. The operation of the switch arm 43 when turned to contact the button 43a has already been described and results in moving all of the switches connected with shaft 45 to the dot-dash positions indicated. As pointed out in the preceding paragraph, this includes the energization of the high tension transformer primaries 12c and 12e through the movement of the switch arm 52. It also results in the opening of the shunts around the transformer secondaries 12d and 12f so that all of the transformer secondaries 12b, 12d and 12f are in series to provide the higher voltage utilized in connection with X-ray tube 11. 5 10

When the switch arm 19 is moved to its dot-dash position it selects a different timer especially adapted for therapy. Button 20a is connected through line 84 with switch 85 which initiates the therapy exposure. When this switch is closed, it completes one circuit through line 86, motor 87 and lines 88, and 58, back to the source L4. At the same time, another circuit is completed through line 89, switch 90 and lines 91, 38, relay 39 and line 28 back to the source. Thus, when switch 85 is closed, it energizes relay 39 to close switch 40, starting an exposure. At the same time, motor 87 starts to turn and at the end of a predetermined time, this causes the arm 81a to open switch 90 thus terminating the exposure.

It will be seen from the above description that I have provided apparatus and circuits whereby when a single master control, such as the "Monitor" system described, is turned to a position for radiography it automatically selects the various control circuits suitable for that operation, and at the same time connects the tube 10 in its energizing circuit and selects the transformer secondary 12b for the radiographic operation. On the other hand, when the "Monitor" is turned to a position corresponding to a superficial therapy operation the requisite control circuits for therapy are connected, the switches on shaft 45 are placed in contact with tube 11 to energize the same for therapy and the transformer secondaries 12d and 12f are automatically placed in series with the secondary 12b to supply the higher kilovoltage necessary for the operation of tube 11. It results from this construction that it is possible to construct the transformer secondaries 12d and 12f specially for high efficiency at the higher kilovoltages used for therapy inasmuch as these secondaries are only used at the higher voltages. I am thus enabled to obtain optimum transformer conditions both under radiographic and therapy conditions.

What I claim is:

1. In X-ray apparatus comprising two separate X-ray tubes the second of which has a higher anode kilovoltage requirement than the first, operating means for said tubes including high tension transformer means for energizing the anode to cathode circuits of said X-ray tubes, said transformer means having a plurality of secondaries, control means for said apparatus having at least two positions, control circuits for said first tube only and operatively connected so as to be rendered operative by movement of said control means to one position, said control circuits also including one of said secondaries, control circuits for said second tube only and operatively connected so as to be rendered operative by movement of said control means to another position, and said last named control circuits including another of said secondaries.

2. In X-ray apparatus comprising two sepa-

rate X-ray tubes the second of which has a higher kilovoltage requirement than the first, operating means for said tubes including high tension transformer means for energizing said X-ray tubes, said transformer means having a plurality of primaries with corresponding secondaries, control means for said apparatus having at least two positions, control circuits for said first tube only and operatively connected so as to be rendered operative by movement of said control means to one position, said control circuits also including one of said secondaries, control circuits for said second tube only and operatively connected so as to be rendered operative by movement of said control means to another position, said last named control circuits including circuits for connecting another of said secondaries in series with said one secondary and for causing energization of the primary for said other secondary, and said first named control circuits including means for shunting said other secondary and for causing deenergization of the primary for said other secondary.

3. In X-ray apparatus comprising two separate
25 X-ray tubes one of which is operable at a higher
anode kilovoltage than the other, operating
means for selectively operating one or the other
of said tubes including high tension transformer
means connectable in circuit for energizing one
30 or the other of the anode to cathode circuits of
said X-ray tubes, said transformer means hav-
ing a plurality of secondaries, at least one of
said secondaries having characteristics adapted
specially for use at said higher kilovoltage, and
35 switch means for connecting said one secondary
in a selected one of said tube energizing circuits
only when said tube operable at higher kilovoltage
is in said circuit.

is in said circuit.

4. In X-ray apparatus comprising two separate X-ray tubes one of which is operable at a higher anode kilovoltage than the other, operating means for said tubes including high tension transformer means selectively connectable in circuits for energizing the anode to cathode circuits of said X-ray tubes, said transformer means having a plurality of secondaries, at least one of said secondaries having characteristics adapted specially for use at said higher kilovoltage, switch means for connecting another of said secondaries in said tube energizing circuit for each of said tubes, and second switch means for connecting said one secondary in series with said other secondary only when said tube operable at higher kilovoltage is in said circuit.

55 5. The combination of claim 4 including a circuit providing a shunt around said one secondary and connecting said other secondary directly into said tube energizing circuit, and said switch means including switches for selecting 60 for energization said tube of lower kilovoltage rating and other switches operable in unison with said first named switches for completing said shunt circuit.

6. The combination of claim 4 including a
circuit providing a shunt around said one sec-
ondary and connecting said other secondary di-
rectly into said tube energizing circuit, a primary
controlling said one secondary, a circuit for en-
ergizing said primary, and said switch means
including switches for selecting for energization
said tube of lower kilovoltage rating and other
switches operable in unison with said first named
switches for completing said shunt circuit and
for breaking said primary energizing circuit.

75 7. In X-ray apparatus comprising a higher

voltage X-ray tube and a lower voltage X-ray tube, operating means for said tubes including specialized control circuits for each of said tubes, master control means having a first position operatively connecting said circuits for said tube of lower voltage and having a second position operatively connecting said circuits for said tube of higher voltage, electrically operable switch control means having first and second positions, switches operatively connecting said operating means with said lower and higher voltage tubes respectively when said switch control means is in first and second positions, an electrical circuit for energizing said switch control means, said last named circuit having first switch means responsive to said master control means and having second switch means responsive to said switch control means, said second switch means being movable between first and second positions corresponding to said first and second positions of said switch control means, means operative by said switch control means for so moving said second switch means, said second switch means in first position completing said electrical circuit for energizing said switch control means when said first switch means is in second position, said second switch means in second position completing said electrical circuit for energizing said switch control means when said first switch means is in first position, and means for automatically stopping said switch control means when it has moved from first to second position or vice versa.

8. In X-ray apparatus comprising an X-ray tube for radiography and an X-ray tube for therapy, electrical energizing circuits for each of

5 said tubes, energizing switch means movable between two positions for energizing one or the other of said tubes, a master control having two positions for selecting either radiography or therapy, switch control means operatively connected with said switch means for moving the latter between its two positions, means controlling said switch control means operative when energized to move said switch control means from 10 one of its positions to the other and to then stop, and said last named means having two energizing settings, one setting including said switch control means in therapy position and said master control in radiography position, the other setting including said switch control means 15 in radiography position and said master control in therapy position, whereby upon completing either a therapy or radiography operation, turning of the master control to a position to select the other operation automatically causes said last named means to operate said switch control means through one cycle to move said energizing switch means.
